UNITED STATES PATENT OFFICE.

DANIEL M. LYNN, OF CLINTONVILLE, PENNSYLVANIA.

GAS-RELIEF VALVE FOR OIL-WELLS.

1,238,165.

Specification of Letters Patent. Patented Aug. 28, 1917.

Application filed January 14, 1916. Serial No. 72,132.

To all whom it may concern:

Be it known that I, DANIEL M. LYNN, citizen of the United States, residing at Clintonville, in the county of Venango and 5 State of Pennsylvania, have invented certain new and useful Improvements in Gas-Relief Valves for Oil-Wells, of which the following is a specification.

The object, construction and utility of 10 this invention are herein set forth with sufficient clearness, to enable those skilled in the art of oil production, to make and use the same.

The object of this invention is to simplify 15 the equipment of oil wells, and reduce the cost of such equipment by eliminating the gas pipe through which gas is conducted from the inclosed chamber of the well, beneath the packer, where the oil production of 20 the well gathers.

In nearly all oil wells a wall-packer is used, which is located above the oil-producing stratum, for the purpose of preventing water from passing downward from the 25 higher, water-producing strata, into the lower oil-producing stratum. Where a well is equipped with such wall-packer, it is necessary to provide a gas-escape passage through the packer, for the escape of gas 30 therethrough.

This invention provides a gas-relief valve, whereby the gas in the oil chamber of the well is permitted to pass into, and escape through the oil-tubing of the well, thus dispensing with the usual gas escape passage 35 through the packer and the pipe connected therewith, and in this respect, and to such extent, the equipment of the well is simplified and reduced in cost.

40 I am aware that certain packers for oil wells have been invented which contain valves that are adapted to permit the escape of gas from the oil chamber of the well into the tubing, such a packer being shown in

45 Letters Patent of the United States to Griffin, No. 1,149,751, dated Aug. 10, 1915, and in Letters Patent of the United States to McNallen, No. 1,164,655, dated Dec. 21, 1915. Inasmuch, however, as the valves shown in 50 said patents are not independent of the packer, but are a structural part thereof, and cannot be employed independently of the

packer, as can my valve, I hereby specifically disclaim such construction: My valve may be interposed directly in the tubing and employed with any type of packer that is used 55 in oil wells.

In the drawings, the various figures are as follows:

Figure 1 is a central, vertical section 60 through my improved gas-relief valve.

Fig. 2 is an elevation of same in position in a well.

Fig. 3 is an elevation of a somewhat modified form of valve.

The construction here shown consists of a suitable body 1, the upper end of which is arranged to be connected to the lower end of a wall-packer 2. The lower end of said body 1 is adapted for the attachment of the 70 tubing 3, which extends downward into the fluid 4 in the well, and the lower end of which tubing usually rests upon the bottom of the hole.

Leading from the duct in body 1, is a lateral, vertically-extending branch duct 5, which is provided with a downwardly-disposed opening, into which is inserted a valve-seat 6, with which a suitable valve, as 75 7 co-operates.

As the well is pumped, the fluid production of the well passes up through said tubing 3, and when the pressure of gas in the fluid cavity 8 beneath the packer becomes sufficiently high, it unseats said valve 7 and 85 passes into said lateral branch 5, thence into the tubing 3, through which it escapes from the well.

It is necessary to the proper working of the valve that it be positioned above the fluid 90 4 in the oil-chamber 8 of the well, but it may be positioned anywhere above the surface of the fluid and below the wall-packer 2, or such equivalent of said packer as may be employed.

95 I claim the following:

1. The combination with the tubing of a well having a wall-packer connected thereto, of a gas-escape valve connected to said tubing, positioned intermediate said packer and the fluid of the well and adapted for the escape of gas from the well through said tubing; said valve comprising a suitable body having a valve-closed opening for the 100

entrance of gas thereinto and into the tubing to which said valve is connected.

2. The combination with the tubing of a well and the wall-packer connected to such tubing, of a gas-escape valve connected to such tubing, and adapted for the escape of gas from the oil-chamber of such well through said tubing, said valve being posi-

tioned intermediate said packer and the fluid of the well which is beneath said packer.

In testimony whereof I affix my signature in presence of two witnesses.

DANIEL M. LYNN.

Witnesses:

E. R. INMAN,
M. R. HENDERSON.
